UNITED STATES PATENT OFFICE.

JOHN C. FORSTER, OF PITTSBURGH, PENNSYLVANIA.

HOUSEHOLD TOOL.

Application filed August 8, 1924. Serial No. 730,854.

This invention relates to household tools and more particularly to an improvement over the combination household tool disclosed in Patent No. 970,206 granted to me on September 13, 1910.

The tool disclosed in the said patent includes a can opener having a cutting blade attached to a carrier which is slidably mounted on a supporting member.

10 An object of this invention is to improve, simplify and cheapen the construction of the tool covered by said patent but at the same time to retain all the advantageous features of said tool.

15 A further object is to provide a can opener which will be simple and cheap to manufacture, rugged in construction and positive in operation.

These and other objects, which will be apparent to those skilled in this particular art, are attained by means of the apparatus illustrated, one embodiment of which is shown in the accompanying drawings, in which Figure 1 is a top plan view of a household 20 tool having a can-opener blade embodying this invention; Fig. 2 is a longitudinal section thereof; Fig. 3 is a bottom plan view; and Fig. 4 is a cross-section on the line 4—4 of Fig. 2, showing the cutting blade and carrier in elevation.

The form of tool disclosed in the above mentioned patent includes a slotted support on which is slidably mounted a blade carrier. The cutting blade is formed separately and is secured to the carrier so as to project downwardly through the slot of the supporting member. Such a construction is not only costly but is to some extent objectionable because the knife is liable to become loose on the carrier, and is not as durable in operation as could be desired. The present invention is intended to materially cheapen the cost of manufacture of this tool and at the same time provide a more rugged construction and thus increase the durability and usefulness of the tool. This is done by reconstructing the knife so as to avoid the necessity of employing a separately formed carrier. As shown, the knife is so formed that it projects through the slot of the supporting member and forms a cutting blade on one side and a top lifter on the other.

The illustrated embodiment of my inven-

tion includes a household tool which is provided with a slotted supporting member 5 which forms both a handle for the tool and a support for the can cutting blade. The blade 6 is slidably mounted in the slot 7 of the supporting member and projects outwardly on one side thereof at a right angle. 55 Shoulders 8 and 9 are formed adjacent a narrow neck 10 and in conjunction with the body portion 11 of the blade, provide grooves 12 and 13 for receiving the edges of the slot 7. The body 11 is bent at a right angle to 60 the cutting section of the blade and is slidable along the opposite side of the supporting member 5, between the upturned flanges 14 and 15. The blade is held in the slot by a rivet 16 which is secured to the 65 body portion and extends through the slot. The end of the blade opposite the cutting section is bent at a right angle to the body section and forms a handle 17 for moving the blade to the desired position in the slot. 70 The top of the handle portion is flanged so as to provide a bottle cap remover.

The device is assembled by first passing the cutting section through the slot and then turning the blade so as to position the edges 80 of the slot in the grooves 12 and 13 after which the rivet 16 is riveted in place.

The end of the supporting member is provided with a punch 18 which is adapted to pierce the can top so as to provide a turning 85 center, as is well known in this particular art. The other end of the member 5 is provided with a cap removing device 19 which forms no part of the present invention, but which is described and claimed in the 90 before mentioned patent.

By forming the cutting blade as described, the cost of manufacture is materially less than where the blade is formed as a separate piece secured to a carrier, as has heretofore been the customary practice. The construction is substantially more rugged and the durability of the tool is materially increased.

I claim:

100
A can opener having in combination a slotted supporting member, a one piece member including a body section overlying one side of said slotted supporting member, one end of said body section being bent at right angles and extending through said slot to

form a cutting section and provided with grooves for receiving the edges of said slot, the other end of said body section being bent outwardly in an opposite direction to said cutting section so as to form a handle and a rivet engaging said body section and extending through said slot so as to loosely

secure said cutting member thereto and prevent the displacement of said cutting member when in operation.

In testimony whereof, I have hereunto subscribed my name this 6th day of August, 1924.

JOHN C. FORSTER.
